UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed July 10, 1930. Serial No. 466,929.

This invention relates to fluid pressure tools of the percussive type having automatically actuated valve means for controlling the distribution of the pressure fluid.

One object of the invention is to increase the economy of operation of tools of the described type. Another object is to devise valve mechanism which will reduce the consumption of pressure fluid without correspondingly reducing the efficiency of the tool. Another object is to make such valve mechanism simple, compact, and positive in operation. Other objects will be apparent from the detailed description which follows.

The invention involves the cutting off of the pressure fluid supply at a predetermined position in the movement of the piston and allowing a definite expansion to take place before the exhaust is opened. By preference there is a definite period in both the working and non-working strokes of the piston when the main motive fluid supply is entirely cut off and prevented from entering the piston chamber.

In order to illustrate the invention one concrete embodiment thereof is shown in the accompanying drawings, in which:

Fig. 1 is a longitudinal sectional view, largely diagrammatic and broken away in parts, showing the hammer piston beginning its working stroke;

Fig. 2 is a fragmentary sectional view showing the position of the parts at the time of the movement of the inner valve to cut off the fluid supply to the rear end of the piston chamber;

Fig. 3 is a view similar to Fig. 1 showing the position of the parts at the time when the piston strikes its blow and begins the return movement; and

Fig. 4 is a fragmentary view showing the piston on its rearward or non-working stroke at the point where the inner valve is moved to cut off the fluid supply.

In the embodiment of the invention chosen for the purpose of illustration, the cylinder 5 of a fluid pressure percussive tool is diagrammatically illustrated, the cylinder having therein a reciprocable piston 6 dividing the piston chamber into a rear cylinder cham-

ber 5a and a forward cylinder chamber 5b. Piston 6 is arranged to impart blows to shank 7 of a drill steel supported in a front head 8 either directly or through an interposed anvil block 9 which may be supported in a guide member or bushing 10 interposed between front head 8 and cylinder 5 and in telescoping relation with the same. Cylinder 5 has a main atmospheric exhaust port 5c controlled by piston 6 and overrun by the latter in both directions of its movement.

Motive fluid for actuating piston 6 is admitted in accordance with the usual practice by a throttle valve (not shown) to inlet passages 11 whence it is directed to a valve chamber 5d provided by cylinder 5. Within the valve chamber are supported for reciprocatory movement nested inner and outer tubular valves 12 and 13 which are automatically thrown in timed relation with the movement of piston 6 and both of which control the admission of pressure fluid from inlet 11 to passages 14 and 15 leading to chambers 5a and 5b respectively at the opposite ends of the cylinder. The central bore through inner valve 12 serves as a conduit for passing the motive fluid from inlet 11 to passage 15.

Valve chamber 5d may be lined as shown by a bushing 16 slidably receiving outer valve 13 and have at its ends bearing members 17 and 18 having annular projections or flanges 17a and 18a for centering valves 12 and 13. Inner valve 12 has sliding telescoping engagement with the interior of said projections while outer valve 13 slidably engages the exterior of the projections. Ports 17b through projection 17a under control of both the valves provide for movement of motive fluid from inlet 11 to passage 14 while similar ports 18b through bearing projection 18a under control of both valves provide for movement of pressure fluid from the bore of inner valve 12 to ports 18d and thence to passage 15.

Outer valve 13 has end areas 13a and 13b subjected to air trapped and compressed by the piston near the end of its stroke in each direction to cause shifting of the same. A central groove or recess 19 in the exterior of this valve registers in alternation with auxiliary vent passages 21 and 22, which have 100

ports opening into the piston chamber on opposite sides of main exhaust 5c, and connects the same to an atmospheric vent 23. Similar recesses or grooves 24 and 25 in the exterior 5 of valve 13 on opposite sides of recess 19 register at all times with shift passages 26 and 27 respectively for inner valve 12, communication with the latter being established by ports 24a and 25a through valve 13 which 10 open adjacent pressure areas on valve 12 formed by spaced radial flanges 28 and 29. The space between flanges 28 and 29 is connected at all times to atmospheric vent 23 by port 30 through the recessed portion 19 of 15 outer valve 13. Flanges 28 and 29 have restricted passages 28a and 29a therethrough gradually to bleed the pressure fluid admitted to the areas provided by these flanges by shift passages 26 and 27.

20 The operation of the tool may be described as follows: In Fig. 1 valves 12 and 13 are both at the left or forward position thereby admitting motive fluid from inlet 11 through ports 17b to passage 14 and thence to chamber 25 5a to drive piston 6 on its working or blow stroke. As the piston advances it closes main exhaust 5c but the air in advance of the piston continues to escape through auxiliary exhaust passage 22 and recess 19 in valve 13 to atmospheric vent 23. When the rear end of piston 6 uncovers shift passage 27, pressure fluid passes through the latter and by means of groove 25 and port 25a in valve 13 has access to the pressure area on inner valve 12 provided by flange 29 with the result that the 30 valve moves to its right or rearward position (Fig. 2), thereby closing ports 17b and cutting off admission of motive fluid to passage 14. The relative positions of the moving 35 parts are now shown in Fig. 2. Further inflow of motive fluid to chamber 5a being prevented by inner valve 12, and as valve 13 has not moved from its original position, pressure fluid is now cut off from both passages 14 and 40 15. On account of the expansiveness of the motive fluid already admitted to chamber 5a, the piston will continue in the direction of the arrow with increased speed and force. Just before piston 6 strikes its blow it closes 45 auxiliary vent passage 22 whereupon the air in advance of the piston is trapped and compressed against the end area 13b of valve 13 so that it is moved to the right or rear position, the piston having meanwhile overrun 50 main exhaust 5c and thereby reduced the pressure in cylinder chamber 5a and upon the rear pressure face 13a of the valve.

With the parts now in the position shown 55 in Fig. 3, motive fluid passes from inlet 11 down through the central bore of inner valve 12 through ports 18b, passages 18d and passage 15 to cylinder chamber 5b to drive piston 6 rearwardly, the air in advance of the piston escaping through main exhaust 5c and after 60 that is sealed through auxiliary exhaust pas-

sage 21 which is now connected to atmospheric vent 23 by groove 19 in outer valve 13. As the piston 6 moves rearwardly, it uncovers shift passage 26 thereby admitting pressure fluid through groove 24 and port 24a in valve 13 against the outer area of flange 28 on inner valve 12, causing the latter to move to its left or forward position (Fig. 4) to close ports 18b and cut off the supply of pressure fluid from the inlet to passage 15. 70 The parts are now in the position shown in Fig. 4 with the pressure fluid supply cut off to both ends of the piston chamber. Piston 6 continues to move rearwardly by expansion of the motive fluid already admitted to chamber 5b and after closing auxiliary exhaust 21 the air trapped in chamber 5a is compressed and made effective against end area 13a of outer valve 13 with the result that the latter also shifts to the left or 80 forward position as piston 6 overruns and uncovers main exhaust 5c. This brings the moving parts again into the positions shown in Fig. 1 and the cycle of operation is complete. 85

To be effective as a percussive tool, it is essential that piston 6 be driven with full power and at maximum speed on the outward or working stroke. Hence the expansion period for motive fluid on this stroke, represented substantially by the distance between auxiliary vent 27 and main exhaust 5c (see Fig. 2 in particular), is relatively brief and only sufficient to get the full effect of the pressure fluid admitted to chamber 5a without 90 checking the speed of piston 6. On the back stroke, however, the purpose is merely to return piston 6 with a reasonable quickness but without power; hence motive fluid is admitted to chamber 5b for a much shorter 95 period, as indicated by a comparison of the distance between admission port 15 and shift passage 26 at the front of the cylinder with the distance between inlet passage 14 and shift passage 27 at the rear end of the piston 100 chamber. Also the expansion period on the back stroke is much longer since it covers substantially the distance between shift passage 26 and main exhaust 5c. 110

From the above it will be noted that both 115 of the nested tubular valves control the admission of pressure fluid to the opposite ends of the piston chamber due to the fact that both cover and uncover identically the same ports, namely 17b and 18b in the spacing and bearing projections 17a and 18a on bearing members 17 and 18 respectively, and that the outer valve 13 controls the auxiliary vents 21 and 22 for the piston chamber and the admission of pressure fluid from cylinder chambers 5a and 5b through shift passages 26 and 27 to the pressure areas provided by flanges 28 and 29 on valve 12. Both of these pressure areas are normally vented by means of the reduced passages 28a and 29a which do 120 125 130

not interfere with the shifting of the valve since they are of very small size as compared with the area of the shift passages. With this arrangement the valve structure is very compact and positive in operation and provides for the expansion of the charge of pressure fluid for driving the piston in both directions thereby effecting economy of operation without impairing the efficiency of the tool. Small ports 31 and 32 may be provided if desired in the ends of outer valve 13 to serve as priming ports for starting the tool and to augment the fluid trapped by piston 6 in cylinder chambers 5a or 5b to trip valve 13.

15 While the invention has been herein disclosed in what is now considered to be a preferred form, it is to be understood that the invention is not limited to the specific details thereof but covers all changes, modifications, 20 and adaptations within the scope of the appended claims.

I claim as my invention:

1. A motive fluid operated motor having a cylinder, a piston reciprocable therein and forming two cylinder chambers, and two pressure thrown valves each controlling admission of motive fluid to both of said chambers, one of said valves being tubular to provide a motive fluid passage axially there-through for conducting the main motive fluid supply to one of said chambers.

2. A motive fluid operated motor having a cylinder, a piston reciprocable therein and forming two cylinder chambers, and two pressure thrown valves each controlling admission of motive fluid to both of said chambers, said valves being in nested relation and one of them having a central axial bore providing a motive fluid passage therethrough for conducting the main motive fluid supply to one of said chambers.

3. A motive fluid operated motor having a cylinder, a piston reciprocable therein and forming two cylinder chambers, and two pressure thrown valves each controlling admission of motive fluid to both of said chambers, said valves being tubular and in coaxial relation and providing an axial passage entirely therethrough for the main motive fluid supply to one of said chambers.

4. A motive fluid operated percussive tool having a cylinder, a piston reciprocable therein, said cylinder having an exhaust port controlled by said piston and a passage leading from said port to atmosphere, and two valves in nested telescoping relation controlling the admission of motive fluid to the opposite ends of said cylinders to reciprocate said piston, said passage being controlled by one of said valves.

5. A motive fluid operated percussive tool having a cylinder, a piston reciprocable therein, said cylinder having axially spaced exhaust ports controlled by said piston and passages leading from said ports to atmos-

phere, and two tubular valves in nested telescoped relation controlling the admission of motive fluid to the opposite ends of said cylinder to reciprocate said piston, one of said valves controlling both said passages.

6. A motive fluid operated percussive tool having a cylinder, a piston reciprocable therein, said cylinder having axially spaced exhaust ports controlled by said piston and passages leading from said ports to atmosphere, and two tubular valves in nested telescoped relation controlling the admission of motive fluid to the opposite ends of said cylinder to reciprocate said piston, one of said valves controlling both said passages, said cylinder having shift ports intermediate said exhaust ports and passages extending therefrom for tripping the other of said valves, and ports through the first of said valves through which motive fluid from said shift ports is made available for tripping the second valve.

7. A motive fluid operated percussive tool having a cylinder, a piston reciprocable therein, said cylinder providing a main exhaust and an auxiliary exhaust ports both positioned so as to be covered and uncovered by said piston, and two valves controlling the admission of motive fluid to the opposite ends of said cylinder, said cylinder providing a passage leading from said auxiliary exhaust port for control by one of said valves.

8. A fluid pressure percussive tool having a cylinder, a piston reciprocable therein, said cylinder providing a main atmospheric exhaust port substantially centrally thereof and auxiliary exhaust ports at opposite sides of said main exhaust, all said ports being under control of said piston, two valves both controlling the admission of pressure fluid to the opposite ends of said cylinder, and passages leading from said auxiliary exhaust ports under control of one of said valves.

9. A fluid pressure percussive tool having a cylinder, a piston reciprocable therein, said cylinder providing a main atmospheric exhaust port substantially centrally thereof and auxiliary exhaust ports at opposite sides of said main exhaust, all said ports being under control of said piston, two valves both controlling the admission of pressure fluid to the opposite ends of said cylinder, and passages leading from said auxiliary exhaust ports under control of one of said valves, and means for shifting the other of said valves by pressure fluid admitted from the piston chamber comprising shift ports in said cylinder intermediate said auxiliary exhausts and said main exhaust.

10. A fluid pressure operated tool comprising a cylinder, a piston reciprocable therein, two valves one within the other and shifting in sequence to control admission of motive fluid to both ends of the cylinder, a shift area on one of said valves, and means includ-

- ing a trip port intermediate the ends of the cylinder under control of said piston and a port in the other of said valves for directing pressure fluid against said area to shift said first-named valve at a predetermined position of said piston in said cylinder.
11. A fluid pressure tool having a cylinder, a piston reciprocable therein, said tool having a valve chamber, two tubular valves in nested relation in said chamber for controlling the admission of motive fluid to said cylinder, fluid pressure means under control of said piston for shifting said valves in timed relation with the movement of said piston, the inner of said valves forming a conduit for motive fluid for one end of said cylinder.
12. A fluid pressure tool having a cylinder, a piston reciprocable therein, said tool having a valve chamber, two tubular valves in nested relation in said chamber for controlling the admission of motive fluid to said cylinder, and centering means at the ends of said valve chamber comprising projections engaged on opposite sides by said valves and ports through said projections controlled by both valves.
13. A fluid pressure tool having a cylinder, a piston reciprocable therein, said tool having a valve chamber, two tubular valves in nested relation in said chamber for controlling the admission of motive fluid to said cylinder, opposed pressure areas on the inner of said valves, means under control of said piston for admitting pressure fluid from the piston chamber to said areas in alternation to shift said valve, and cooperating means on said valves whereby said first-named means are controlled by the relative positions of said valves.
14. A fluid pressure tool having a cylinder, a piston reciprocable therein, said tool having a valve chamber, two tubular valves in nested relation in said chamber for controlling the admission of motive fluid to said cylinder, opposed pressure areas on the inner of said valves, means under control of said piston for admitting pressure fluid from the piston chamber to said areas in alternation to shift said valve, cooperating means on said valve whereby said first-named means are controlled by the relative positions of said valves, and means providing a restricted vent for at least one of said inner valve areas including a port in said outer valve.
15. A fluid pressure tool having a cylinder, a piston reciprocable therein, said tool having a valve chamber, two tubular valves in nested relation to said chamber for controlling the admission of motive fluid to said cylinder, the inner of said valves having spaced flanges providing opposed pressure areas, means controlled by said piston and by the relative positions of said valves for directing pressure fluid from the piston chamber to said areas in alternation to shift
- said inner valve, and means providing continuously open vents of restricted size for said areas.
16. A fluid pressure tool having a cylinder, a piston reciprocable therein, said tool having a valve chamber, two tubular valves in nested relation in said chamber for controlling the admission of motive fluid to said cylinder, the inner of said valves having spaced flanges providing opposed pressure areas, means controlled by said piston and by the relative positions of said valves for directing pressure fluid from the piston chamber to said areas in alternation to shift said inner valve, said valve flanges having restricted bores therethrough, and means continuously venting the space between said flanges including a port in said outer valve.
17. In a fluid pressure percussive motor, in combination, two valves in nested telescoping relation, means on one of said valves to provide opposed pressure areas, and cooperating means on said valves providing for access of motive fluid to said areas in alternation dependent upon the relative positions of said valves.
18. In a fluid pressure percussive motor, in combination, two tubular valves in nested telescoping relation, flanges on the inner valve providing opposed pressure areas, and means on the other of said valves for admitting pressure fluid to said areas in alternation dependent upon the relative positions of said valves.
19. In a fluid pressure percussive motor, tubular valves in nested telescoped relation, flanges on the inner valve providing opposed pressure areas, the outer valve having ports controlled by said flanges for admitting motive fluid in alternation to said areas, and a vent port therethrough in constant communication with the space between said flanges.
20. In a fluid pressure percussive motor, tubular valves in nested telescoped relation, flanges on the inner valve providing opposed pressure areas and having restricted ports therethrough, the outer valve having ports controlled by said flanges for admitting motive fluid in alternation to said areas and a vent port therethrough in constant communication with the space between said flanges.
21. A valve assembly for a fluid pressure motor comprising a bushing or casing member, inner and outer tubular valves in nested relation within said bushing, the outer valve slidably engaging said bushing, end members for said bushing having annular projections whose outer and inner surfaces provide bearings for said valves, said projections having ports therethrough controlled by both said valves.
22. A valve assembly for a fluid pressure motor comprising a bushing or casing member, inner and outer tubular valves in nested

relation within said bushing, the outer valve slidably engaging said bushing, end members for said bushing having annular projections whose outer and inner surfaces provide bearings for said valves, said projections having ports therethrough controlled by both said valves, and means on one of said valves for registration with the ports on one of said projections to pass a limited amount of motive fluid when the said valve is in position to close said ports.

23. A valve assembly for a fluid pressure motor comprising a bushing or casing member, inner and outer tubular valves in nested relation within said bushing, the outer valve slidably engaging said bushing, end members for said bushing having annular projections whose outer and inner surfaces provide bearings for said valves, said projections having ports therethrough controlled by both said valves, and means on one of said valves for registration with said projection ports in alternation to pass only a limited amount of motive fluid when the said valve is in position to close said ports.

24. A valve assembly for a fluid pressure motor comprising a bushing or casing member, inner and outer tubular valves in nested relation within said bushing, the outer valve slidably engaging said bushing, end members for said bushing having annular projections whose outer and inner surfaces provide bearings for said valves, said projections having ports therethrough controlled by both said valves, said outer valve having restricted ports arranged to register in alternation with the ports in said projections when the valve is in position to close said last-named ports.

40 Signed by me at Detroit, in the county of Wayne and State of Michigan this 3 day of July, 1930.

GUSTAVE M. NELL.
